UNITED STATES PATENT OFFICE.

MEINHARD WITTE, OF MINNEAPOLIS, MINNESOTA.

RADIATOR SUPPORT.

Application filed June 18, 1924. Serial No. 720,792.

My invention relates to automobile radiators and is particularly directed to improved means for supporting the same, all as will hereinafter more fully appear. The invention may be applied to automobiles and to radiators of various different designs, but, as illustrated in the drawings, it is especially designed for application to Ford cars. In Ford cars, it is customary to support the radiator on the side frames, the front ends of which latter are supported from the front spring by a front cross member. In the customary arrangement, the side plates of the radiator have had outwardly projecting supporting lugs with bolt holes through which and bolt holes in the side frames, anchoring bolts have been applied. In said old or customary arrangement, if the front cross member should become broken or spread, as frequently happens, the side frames will spread and this spreading strain will draw outward on the radiator side plates and distort or tear the same loose, thus very greatly damaging the radiator and, in any event, putting the same out of action. I have provided an extremely simple and efficient way of preventing the radiator from being damaged by breaking or spreading of the front cross member or side frames, and this feature is illustrated in the accompanying drawings, wherein like characters indicate like parts throughout the several views.

Referring to the drawings:

Fig. 1 is a front elevation showing a radiator connected to the side frames of a Ford car, in accordance with my invention;

Fig. 2 is a plan view of the parts shown in Fig. 1, but with some parts sectioned and with some parts removed;

Fig. 3 is a side elevation of the radiator shown in Figs. 1 and 2, but with the side frames, front cross member and front spring removed;

Fig. 4 is a fragmentary vertical section taken on the line 4—4 of Fig. 2, some parts being shown in full;

Fig. 5 is a side elevation showing one of the side plates of the radiator;

Fig. 6 is a perspective view showing one of the radiator-anchoring brackets removed from the cooperating side plate shown in Fig. 5;

Fig. 7 is a side elevation showing the lower portion of the radiator side plate and the anchoring bracket applied thereto;

Fig. 8 is an enlarged horizontal section on the line 8—8 of Fig. 7; and

Fig. 9 is a view corresponding to Fig. 7, but in which the radiator-anchoring bracket is indicated by dotted lines only.

The numeral 10 indicates the front cross member, which, by nut-equipped U-bolts 11, is rigidly secured to the front spring 12, as in the ordinary Ford car. The numeral 13 indicates the side frames, which, as shown, are channel bars, the front ends of which are rigidly secured to the upturned ends of the cross member 10 by rivets and riveted gusset plates 14, in the customary way. The structure just described is that of an ordinary Ford car. Also in the ordinary Ford car, the outstanding brackets from the radiator side plates are anchored to the upper flanges of the side frames 13 by bolts 15 passed through perforations in the flanges of said side frames and equipped above and below the said flange with springs 16, spring caps 17, and nuts 18. Anchoring bolts equipped as just described and which are found in the Ford car, may be conveniently used as anchoring devices for my improved radiator supporting and attaching means, but, of course, anchoring bolts or devices of various different types may be employed. The radiator comprises a core structure 19, a lower tank 20, an upper tank 21, and radiator side plates 22. So far as this invention is concerned, the core 19 and tanks 20 and 21 may be of any suitable arrangement. The radiator side plates 22, however, involve certain novel features which will now be noted.

The upper tank 21, longitudinally of the car, is much wider than the lower tank 20 and, hence, to form the best kind of connection and brace between the ends of the tanks, said side plates 22 are made wider at their upper than at their lower ends, or, otherwise stated, are downwardly tapered so that, at their lower ends, they are approximately the width of the lower tank 20, but at their upper ends are much wider than said lower tank, though preferably more narrow than the said upper tank. The plates 22 have in-turned flanges that overlap the side edges of the radiator core and, at their lower and upper ends, they are provided respectively with extended ends or anchoring flanges 23 and 24. The anchoring flanges 23 are bent to fit the inclined ends of the lower tank 20 and are rigidly secured to the ends of said lower tank.

preferably by a so-called "sweating" process; and to facilitate this sweating connection, said flanges 23 are formed with sweat holes 23^a and 23^b to receive solder, (see particularly Figs. 5, 7 and 9). The upper anchoring flange 24 is bent to fit the rounded beveled ends of the upper tank 21 and is secured thereto preferably by the sweating process; and to facilitate this process, said flange 24 is provided with sweat holes 24^a to receive solder, (see particularly Fig. 5).

The anchoring lugs used in my improved radiator-supporting means are preferably short angle iron sections 25, the vertical flanges of which are rigidly secured to the lower end portions of the radiator side plates 22, preferably by spot welding at various different points, such as indicated by the dotted circles marked 26 on Fig. 9. Also, to take the shear between these brackets and the radiator side plates, the vertical flanges of the brackets are preferably provided with laterally pressed dowel-acting bosses 27 that fit through perforations 28 in the side plates, (see particularly Figs. 5 and 8). The outstanding horizontal flanges of the angular lugs 25 are, as a salient feature of the invention, provided with open seats or with notches 29 that open at the outer edge of the said flanges. In this arrangement, the notched horizontal flanges of the anchoring lugs 25 are placed on the upper flanges of the side frames 13, the bolts 15 are passed through the notches 29, and the upper springs 31 press the said notched flanges tightly upon the upper flanges of the side frames, as best shown in Fig. 4. With this arrangement, as is evident, if the front cross member 10 should be broken or bent or if the side frames or

either thereof should become loose from the ends of the said front cross member so as to permit spreading of the side frames, the bolts 15 would simply move outward in or out of the notches 29 and the radiator side plates would thereby be relieved from such strains as would tend to break or bend the same or to tear the same loose from the radiator tanks. This construction, in actual practice, has been found highly important for reasons already clearly indicated.

To reinforce and stiffen the radiator side plates 22, they are provided with long vertical laterally pressed reinforcing ribs 30 that extend from the upper portion nearly or quite down to the anchoring lugs 25. For the same reason, the lower ends of the side plates 20 are further provided between the reinforcing ribs 30 with relatively short laterally pressed reinforcing ribs 31 that extend from points below the tops of the lugs 25 to points considerably above the lower extremities of the ribs 30. These ribs 31 give a good stiffening reinforcement immediately above the lugs 25. Widening of the side plates toward their upper ends very greatly increases the forward and rearward reinforcement between the lower and upper tanks 20 and 21.

What I claim is:

A radiator side plate that is channel-shaped in cross section and having on its web dowel-acting bosses, and an angle anchoring lug having perforations in one of its flanges into which said bosses extend for positioning said angle on the side plate, said lug being rigidly secured to the side plate.

In testimony whereof I affix my signature.

MEINHARD WITTE.
